UNITED STATES PATENT OFFICE.

YOSHIMASA MASUZAWA, OF ARMONA, CALIFORNIA.

SANITARY ATTACHMENT FOR TOILET-SEATS.

1,237,934.

Specification of Letters Patent. Patented Aug. 21, 1917.

Application filed January 31, 1916. Serial No. 75,422.

To all whom it may concern:

Be it known that I, YOSHIMASA MASUZAWA, a subject of the Emperor of Japan, residing at Armona, in the county of Kings 5 and State of California, have invented a new and useful Sanitary Attachment for Toilet- Seats, of which the following is a specification.

The present invention relates to an improved attachment for toilet seats, and has for an object to provide a device for supporting a number of sheets, of paper, or the like, conveniently over the toilet seat, to be used one for each person, to prevent contact of the person with the seat, and thus eliminate the liability of infection; to provide means for guiding the sheets into proper position upon the seat, as they are drawn down for use; to provide a device 15 which admits of the free raising and lowering of the seat and its cover; to provide a device which supports a large number of sheets and automatically feeds the outermost sheet into a position to be grasped; 20 and to provide a combined support and cutter to hold the sheets in place to be grasped and to cut the same free from the support when they are being pulled down for use.

Another object of the present invention is 25 to provide a support for the sheets which may be placed above a low down flushing tank, or below a high flushing tank, and which may be easily fitted to any type of toilet seat.

Other objects and advantages of this invention will be brought out in the following specific disclosure of the present preferred embodiment thereof, the same being shown in the accompanying drawing, wherein—

Figure 1 is a front elevation of the device of this invention applied to a toilet seat, and being arranged beneath an elevated flushing tank.

Fig. 2 is a horizontal sectional view, taken 45 through Fig. 1, on the line 2—2, and looking downwardly on the seat in the direction indicated by the arrow.

Fig. 3 is a vertical sectional view through

the sheet support, taken on the line 3—3 of Fig. 1.

Fig. 4 is an outer side elevational view of the support with the sheets removed therefrom.

Fig. 5 is a detail enlarged top plan view of one of the upper supporting studs carried by the support.

Referring to the drawing, wherein like parts are designated by similar numerals of reference throughout the several views, 10 designates a bowl of the usual construction 60 mounted on a pedestal 11 and provided with a seat 12 of the usual form, and a cover 13 therefor. The seat 12 and cover 13 are provided in the usual manner with hinge members 14 through which pass bolts 15, in order 65 to hingedly connect both the seat and the cover to posts 16 which rise from the back board or support 17 usually arranged in rear of the seat and the cover. In the present instance this support 17 is shown in the 70 form of a flat base board lying horizontally and substantially in the plane of the seat 12. Arranged above the bowl 10 at a considerable height is a flushing tank 18, which is connected to the bowl 10 by a flushing pipe 75 19 extending downwardly and through the base board 17.

The improved attachment comprises, broadly, a support for a stack of sheets of paper, and a guide to engage each sheet of 80 paper and direct it downwardly into proper position upon the seat 12. The support comprises a base plate 20 having preferably at its upper and lower edges outstanding ears 21 adapted to be bent backwardly and 85 secured against the face of the wall. The base plate 20 is thus supported in slightly spaced relation from the wall and in a vertical position. Outstanding from the upper end of the base plate, and being spaced toward the opposite corners thereof, is a pair 90 of upper studs 22, round in contour, and notched at their opposite sides, to provide heads 23 with abrupt inwardly facing shoulders 24. The reduced portions of the studs 95 22, immediately behind the heads 23, are

beveled at their opposite sides and have such sides converging upwardly to provide a longitudinal cutting or knife edge 25 which slopes outwardly and downwardly behind the head. The lower end of the plate 20 is provided with a pair of spaced apart hollow studs 26 in the form of sleeves or tubes which extend outwardly in parallelism with the upper studs 22, and are preferably spaced farther toward the opposite lateral edges of the plate to dispose the lower studs 26 as far apart as possible. The outer ends of the studs 26 are left open. Placed over the studs 22 and 26 are a plurality of sheets 27, of paper, or the like, and which are provided with apertures through which the studs are adapted to snugly fit. The base plate 20 is provided with a follower 28, in the form of a flat plate of slightly less width than that of the base plate 20, and provided upon its lower end with overturned tongues 29 rolled about a transverse rod 30, which is secured in spaced relation across the lower outer face of the base plate by means of straps 31, the latter being riveted or otherwise suitably secured to the base plate after being rolled around the rod 30. Thus, the follower plate 28 is hinged at its lower end upon the lower end of the base plate. Springs 32, one or more being employed, and preferably being of the leaf type as shown, are secured to the base plate at one end, as at 33, and bear at their opposite free ends against the inner side of the follower plate 28 to force the latter outwardly against the sheets 27 and crowd the sheets forwardly upon the upper pair of studs 22. This crowding forwardly of the sheets presses the outermost sheet against the flat shoulders 24 of the heads 23 to retain the stack of sheets from accidental displacement from the support. As soon, however, as it is desired to detach a sheet from the support, it is only necessary to draw the outermost sheet downwardly when the sheet comes in contact with the upwardly facing knife 25 on each stud, and is severed thereby, so that the sheet may be quickly and easily removed from the support. The follower 28, under the yielding pressure of the springs 32 advances the stack of sheets the thickness of one sheet each time a sheet is removed, so as to hold the sheets always in proper position for detachment.

The guide employed is in the form of a single length of relatively heavy wire bent substantially U-shaped, the opposite arms of which constitute a pair of spaced apart guide rods 34 adapted to extend upwardly at the opposite sides of the seat and the cover. As will be noted particularly from Fig. 2, the lower end of the U-shaped guide is offset backwardly to provide the guide with a supporting base 35, adapted to rest

flat upon the supporting board 17. This horizontal portion of the guide is held flat upon the board 17 by an attaching plate 36 secured by screws, or the like, to the board 17. It will be noted that the opposite ends of the base 35 of the guide diverge outwardly from one another to a point which is located at a substantial distance beyond the opposite lateral edges of both the seat 12 and the cover 13, so that the vertical guide rods 34 are disposed far out beyond the opposite edges of the seat and the cover, so as not to interfere with the raising and lowering thereof. At the same time, the extending forwardly of the base 35 of the guide so positions the guide rods 34 that they direct the lower end of the sheets forwardly of the cover 13 and out of contact therewith, so that the sheet 27 when drawn down will lie flat upon the unobstructed seat. The upper ends of the guide rods 34 are turned inwardly, as shown to advantage in Fig. 3, to provide fingers 37 which fit into the outer open ends of the lower studs 26, so as to receive from the studs the lower ends of the sheets 27, and to thus hold and guide the sheets 27 into proper place over the seat.

The sheet 27 may be of any desired form, but is preferably made of a size to completely cover the seat 12, and is provided with a central severed portion 38 held in place in the middle of the sheet by imperforate tabs 39, which are relatively narrow and which may be arranged in any desired manner, such as the three indicated in Fig. 1. The central section 38 is removable and is perforated along desired lines as at 40 to enable the easy separation of the section 38 into the desired number of smaller parts.

Each sheet 27 is provided at the forward side of the opening therein with an inwardly extending protecting tongue 41.

When it is desired to withdraw a sheet 27 and apply it to the seat 12, it is only necessary to draw the upper portion of the sheet 27 downwardly and engage the same with the knife edges 25 of the upper studs. These knife edges thus cut the sheet and admit of its easy detachment from the studs 22. The sheet is now swung down, and the lower end thereof slips from the tubular studs 26 onto the guide rods 34, and as the sheet is allowed to drop, or is carried down, the guide rods direct the sheet into proper alignment over the seat. As soon as one sheet is removed from the stack, the springs 32 urge the follower plate 28 forwardly and advance the stack upon the upper studs 22. To replace a stack of sheets upon the support, it is only necessary to draw the resilient guide rods 34 outwardly to disengage the fingers 37 thereof from the lower tubular studs 26. When the guide rods 34 are thus drawn outwardly

sufficiently to be out of the way, the new stack of sheets may be forced, by slight pressure, over the upper and lower studs 22 and 26 against the tension of the springs 32. 5 The fingers 37 are now sprung back into place when the sheets are in position to be used.

It is, of course, understood that various changes and modifications may be made in 10 the above specifically set forth structure within the scope of the claims without departing from the spirit of the invention, so as to adapt the device of this invention to various conditions which may be found in 15 the mounting of the device, and for the purposes of design.

What is claimed is:—

1. The combination with a toilet seat having a cover hinged at the rear thereof, of a 20 support mounted above the seat and adapted to carry a stack of sheets, and spaced guides in engagement with said sheets and extending downwardly from said support to points near to each side of the seat, forwardly 25 of the rear edge thereof and of the hinge of the cover, said guides being spaced apart sufficiently to allow the cover to swing backwardly between them.

2. The combination with a toilet seat, of 30 a support arranged above the toilet seat and adapted to carry a stack of sheets thereon, heads carried by the support for engagement with the sheets to hold the same from outward displacement, cutters arranged behind 35 said heads for cutting the sheets upon their vertical downward movement behind the heads, and guides engaging through the lower ends of the sheets and extending downwardly at the opposite sides of said 40 seat.

3. The combination with a toilet seat, of a support mounted above the seat and adapted to carry a stack of sheets, a guiding member secured behind said seat and having forwardly 45 diverging and upwardly extending arms spaced laterally from the edges of the seat and being turned inwardly at their upper ends for engagement through the lower ends of the sheets to retain and guide the same, said guiding arms being resilient and adapted for withdrawal from the lower end 50 of the support to admit the removal and replacement of a stack of sheets.

4. The combination with a toilet seat, of 55 a support arranged above the toilet seat and comprising a base plate for securement against the wall, a follower plate mounted on the base plate, a spring for urging the follower plate outwardly, upper and lower 60 studs outstanding from the base plate and adapted to receive a stack of sheets thereover, and a pair of resilient guiding rods extending upwardly from the opposite sides of the seat and adapted for yielding en-

gagement with the lower studs to receive the 65 lower ends of the sheets therefrom when detached, and to admit of the springing outwardly of the guides and the ready application of a stack of sheets to the support.

5. In a device as specified, a support having 70 outstanding studs for engagement through a stack of sheets, and having heads on their outer ends adapted to hold the stack against outward displacement, the studs having upwardly facing knife edges immediately 75 behind the heads to cut and release the sheets when the latter are drawn downwardly from behind the heads.

6. The combination with a toilet seat having 80 a cover hinged at the rear thereof, of a support mounted above the seat and adapted to carry a stack of sheets, and spaced guides extending downwardly from said support to points at each side of the seat, forwardly 85 of the rear edge thereof and the hinge of the cover and substantially in the same horizontal plane therewith, said guides being spaced apart sufficiently to allow the cover to swing backwardly between the guides, the lower portion of said guides being directed to the 90 rear of the seat and suitably supported, the upper ends of the guides removably engaging the support and sheets.

7. In a device as specified, a supporting 95 stud for a stack of sheets, said stud having registering notches in its opposite side walls, said walls converging upwardly to provide a cutting edge at the top of the stud and a head outwardly of the cutting edge, and a spring pressed follower bearing against the 100 stack of sheets to yieldingly hold the outermost sheet against the head, the cutting edge being adapted to cut the sheets free of the stud as they are drawn downwardly one at a time.

8. In a device as specified, a flat plate adapted for securement against a wall, a second plate hinged at its lower end to the lower end of said flat plate and comprising a follower, a pair of leaf springs secured at 110 one end to the flat plate and bearing at their free ends against the free end of the follower to urge the latter outwardly from the flat plate, a pair of studs outstanding from the flat plate, and passing through said follower, a pair of lower studs carried by the flat plate and extending outwardly therefrom and having open outer ends, said studs being adapted to receive the upper and lower portions of a stack of sheets thereover, heads on the upper studs adapted to engage the outermost sheet and hold the same from displacement under tension of the follower, and a pair of guides detachably engaging in the lower studs and adapted to receive said 115 sheets one at a time when released from the upper studs.

9. A device as specified comprising a sup-

port adapted for attachment to a wall over
a toilet seat, studs outstanding from the
support for engagement with a stack of
sheets, and a guide beneath the support, said
5 guide comprising a single length of wire
bent substantially U-shape to provide op-
posed guiding arms extending vertically up-
ward from the opposite sides of the toilet
seat, and having its lower end offset in-
10 wardly for securement behind the seat, the
upper extremities of said guiding arms

being turned inwardly for engagement
through the stack of sheets to receive the
same one at a time when released from said
studs.

15

In testimony, that I claim the foregoing
as my own, I have hereto affixed my signa-
ture in the presence of two witnesses.
